UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING-MACHINE.

1,278,811.

Specification of Letters Patent. Patented Sept. 10, 1918.

Application filed May 3, 1915. Serial No. 25,502.

To all whom it may concern:

Be it known that I, PERLEY R. GLASS, a citizen of the United States, residing at Brookline, in the county of Norfolk and State of Massachusetts, have invented certain Improvements in Eyeletting-Machines, of which the following description, in connection with the accompanying drawings, is a specification, like reference characters 10 on the drawings indicating like parts in the several figures.

This invention relates to machines for setting blind or invisible eyelets in sheet material such as the uppers of boots and 15 shoes.

In setting blind or invisible eyelets by mechanism as heretofore constructed difficulty has been encountered in securing consistently the desired effect upon the eyelets. This has proved very objectionable from the standpoint of the shoe manufacturer because it has necessitated the frequent removal and replacement of imperfectly inserted eyelets, an operation which is performed with difficulty in shoes of this class. An object of the present invention, accordingly, is to provide, for setting blind or invisible eyelets, novel mechanism which may be depended upon to clench the barrel of 30 each eyelet at the proper point in the upper, that is, upon the desired layer of lining or stiffening material, to split the eyelet barrel evenly, turn it uniformly and flatten its clenched end in the work.

To this end an important feature of the invention consists in a novel organization for perforating the outer part of the quarter and clenching the barrel of an eyelet between the parts of the work. In the illustrated embodiment this organization comprises a punching tool having its punching end beveled or otherwise shaped to constitute an upsetting surface. I have discovered that the end of a punching tool which is tapered to form a cutting edge may be utilized with good advantage for upsetting the end of an eyelet barrel provided the eyelet is properly guided into engagement with such surface. A punching tool of this character lends itself with particular facility to the requirements of the blind or invisible eyeletting operation because the step of per-

forating the outer portion of the quarter results in locating the upsetting surface at the proper point for clenching the barrel of 55 an eyelet inserted through the lining portion.

Another feature of the invention consists in a support upon which may be placed a shoe quarter comprising an outer and a lining portion in combination with a tubular punch movable to perforate the upper portion of the quarter while the latter is yieldingly backed up by the lining portion. By carrying out the punching operation under 60 these conditions a hole is formed in the outer part of the quarter having a cleanly cut margin. This is an important advantage incident to the present invention and eliminates the ragged and misshapen holes frequently produced heretofore in blind or invisible eyelet work.

Another important feature of the invention consists in means for forming a perforation in one portion of a shoe quarter 75 in alignment with a perforation previously formed in the other portion thereof. Such means is believed to be broadly new as heretofore both portions of the upper have been perforated in substantially a single operation. As herein shown, the desired result is effected by a male punching tool movable to enter the bore of the tubular punch and so to cut a perforation in the lining portion by a punch and die action.

The combination of means for punching one portion of a shoe quarter at one time and means for punching the other portion of the quarter at another time is also believed to be novel. In this aspect of the 90 invention another important feature consists in a tubular punching member and a solid punching member one of which is constructed and arranged to perforate independently one portion of a shoe quarter and to perforate the other portion in coöperation with the other punching member.

It is important to guide the barrel of the eyelet as it is inserted through the perforation in the lining portion and to direct it 100 into engagement with the upsetting surface of the punch previously inserted through the outer portion. Any desired means may be employed for this function but as herein

2
shown, and in accordance with another feature of the invention, the male punching member serves this purpose.

The novel method of setting blind or invisible eyelets herein shown as capable of being carried out by the improved mechanism of the invention is not claimed herein as it forms the subject-matter of my pending application, Serial No. 249,986, filed 10 August 15, 1918.

The features above discussed and others incident to the invention will be best understood and appreciated from the following description of a machine embodying the invention selected for purposes of illustration and shown in the accompanying drawing, in which,—

Figure 1 is a view in perspective of the operating parts of an eyeletting machine in 20 which the present invention is embodied;

Figs. 2, 3 and 4 illustrate on a large scale the successive positions of the punching and setting tools in setting invisible eyelets;

Fig. 5 is a view in perspective of the 25 punching and setting tools;

Fig. 6 is a view in perspective of a portion of a shoe quarter having invisible eyelets set therein, and

Fig. 7 is a view in perspective of an up- 30 setting tool of modified form.

The invention is herein illustrated as embodied in an eyeletting machine of the type disclosed in Letters Patent of the United States No. 1,228,768, granted June 5, 1917, 35 upon my prior application, although the invention is not limited to that machine or to machines of any particular type.

The machine frame 2 is suitably shaped to support the moving parts of the machine 40 and provided with vertical guideways in which reciprocates the plunger 6 having adjustably mounted in its upper end the lower or eyelet carrying set 9. Secured to the plunger 6 is a split collar 8 having ears on 45 its rear side through which extends a clamping bolt. This bolt is extended beyond the ears of the split collar and forms the journal for a block 10. The block 10 is received between the jaws of a forked lever 14 50 journaled on a shaft 16 suitably supported in the machine frame and oscillated by means not herein shown to impart vertical reciprocation to the eyelet carrying set 9.

The frame 2 is formed with an overhanging portion having two sets of horizontal bearings, one for the upper rod 26 which is held stationary, and the other for the lower rod 28 which is arranged to slide freely in its bearings. The horizontal rods 26 and 28 60 carry the feed frame 32. At its upper end the feed frame is free to slide upon the rod 26 while at its lower end it is secured to the rod 28 and carries the latter with it in its transverse movements to feed the work.

65 The feed frame 32 is provided with vertical

guideways for the plunger 34 which carries at its lower end the combined punch and upsetting tool 40. The plunger 34 is moved downwardly in the punching operation, as will be presently described, and at the conclusion of the feeding operation is again elevated. These vertical movements are effected by toggle mechanism including a pair of links 42 and a pair of bell crank levers 44 journaled at their upper ends about the 75 stationary rod 26 and connecting the knuckle of the toggle with the forward end of a link 48. The link at its rear end may be connected to any suitable actuating mechanism for imparting the required movement 80 to the toggle.

Transverse movement is imparted to the tool 40 for feeding the work by sliding the feeding frame 32 transversely. To this end the frame is provided with a rearwardly 85 extending arm to which is pivotally secured a block 80. The block 80 is received between the jaws of a forked arm 82 journaled upon a stationary vertical shaft 86 and connected to a sleeve 88 having an outwardly 90 extending arm 90. The latter is connected through a link 92 to any suitable form of spacing mechanism by which the desired feeding movement is imparted to the feed frame and the tool 40.

A cutting block 69 and a work plate 71 are mounted upon the machine frame 2 and a presser foot 72 is provided for holding the work in place between the feeding steps. A raceway 120 is also provided for supplying 100 eyelets to the eyelet carrying set 9. The parts of the machine above described, and those not herein shown, in structure and operation correspond to the similar parts of the eyeletting machine disclosed in my prior 105 application above identified. Only sufficient parts of this machine have been illustrated to render clear the operation of the machine, the remainder having been omitted for the sake of clearness.

The punching and upsetting tool 40 is provided with a threaded shank 41 which is received within the lower end of the plunger 34. This tool is primarily a tubular punch having its lower end 42 tapered to form a 115 cutting edge and incidentally an upsetting surface as will presently appear. As shown in Figs. 2 to 5 the end 42 of the tool 40 is beveled or tapered in a concave manner and above the tapered portion is a cylindrical 120 portion 43. Above the portion 43 the tool is enlarged and provided with a threaded portion 44 upon which is adjustably held a stop 45 which comprises a threaded nut.

The plunger 34 and tool 40 are so constructed and arranged that when the plunger is depressed the cutting edge of the tool will be forced through the outer portion 20 of a shoe quarter, or the upper layer of the work, supported upon the cutting block 69 130

as shown in Fig. 2 and will enter slightly the material of the layer 21 beneath. In order to render this operation more accurate the stop 45 is so adjusted upon the threaded portion 44 of the tool 40 that the exposed length of the cylindrical portion 43 of the tool is substantially equal to the thickness of the portion 20 of the work. It will thus be seen that the lower layers 21 and 22 of the work will constitute a yielding backing for the layer 20 which is to be perforated by the tool 40. As already pointed out the punching operation under these circumstances produces a very cleanly punched hole in the upper portion 20 of the work.

The eyelet carrying set 9 is shaped at its upper end to receive the flange of the eyelet to be inserted and with an upwardly projecting punching member 11 of such diameter as to enter the bore of the tubular punching tool 40. At its upper end the punching member 11 is beveled at 13 upon one side so that its punching action, in coöperation with the tubular punching member 40, will be of a shearing punch and die nature. To insure more certainly the proper entering of the punching member 11 in the bore of the tubular punching member the opposite side of the upper end of the member 11 is slightly beveled. The punching member 11 occupies the position in the eyelet carrying set 9 of the usual center spindle and as such spindle it has the function of taking an eyelet from the raceway and holding it in position during the upward movement of the eyelet carrying set. In the present construction the punching member 11 also serves as a positive guide for directing the barrel of the eyelet through the lower portion of the work and into engagement with the upsetting surface upon the end 42 of the tubular punching tool.

In operating the machine herein illustrated the shoe quarter is placed upon the work plate 71 with the point at which the first eyelet is to be set above the cutting block 69 and in alignment with the tubular punching tool 40. The machine is then set in operation and the plunger 34 depressed carrying the tubular punching tool through the upper portion 20 of the quarter and embedding its end slightly in the underneath portion 21 of the quarter. Fig. 2 of the drawing shows the punching tool in this position. The tool 40 is then moved transversely toward the left feeding the entire quarter with it until it comes into a position in alignment with and above the eyelet carrying set 9. The plunger 6 is then elevated and an eyelet supplied to the punching member 11 during the upward movement thereof. The punching member 11 then encounters the underside of the lower portion 22 of the quarter and in its upward movement enters the bore of the tool 40 shearing

out a hole in the previously unperforated portions of the quarter. Fig. 3 illustrates the punching member 11 as partially entered into the bore of the tubular punch 40. As the upward movement of the eyelet carrying set 9 continues the member 11 advances up the bore of the tool 40 pushing the punchings ahead of it and at the same time guiding the end of the eyelet barrel through the lower portion of the quarter and into engagement with the upsetting surface of the end 42 of the tubular punch. The end of the eyelet barrel is split by this surface and turned outwardly beneath the lower surface of the upper portion 20 of the work. When the tools reach their final position, as shown in Fig. 4, the clenched end of the barrel is flattened down by the pressure upon it of the material of the upper portion 20 reinforced by the lower face of the stop 45.

The work herein illustrated comprises a shoe quarter made up of an outer or leather portion 20 and a lining portion which in turn is made up of a stiffening strip 21 of canvas or similar material and a leather part 22. For convenience the invisible eyelet will be described as being set in the lining part of the work, that is to say with its flange against one surface of the part 22 and its clenched end against the oppositely disposed surface of the stiffening strip 21 but it will be apparent that if desired the eyelet may be set in one layer only of the work. This would be accomplished if the tubular punch 40 were adjusted to pass through the intermediate strip 21 in its punching operation.

Fig. 7 illustrates a tubular punching tool having its cutting edge formed by a convex instead of a concave bevel. A tool of this description has been found to operate advantageously upon certain classes of work and may be substituted for the tool shown in Figs. 2 to 5 without affecting the operation of the machine as above outlined.

In the foregoing description the operation of setting an invisible eyelet has been described, such an eyelet being one set in the lining portion of a quarter beneath the hole formed in the outer or leather portion. The operation of setting a blind eyelet is similar in all respects except that the work is presented to the machine in an inverted position, that is to say with the lining uppermost. The eyelet then set will be disposed with its flange upon the outer surface of the shoe and its clenched end within the lining portion so that only a hole for the passage of the lacing appears within the shoe.

Having thus described my invention, I claim as new and desire to secure by Letters Patent of the United States:

1. In a machine for setting blind or invisible eyelets, a tubular punching member, and a solid punching member, one of which

is constructed and arranged to perforate independently one portion of a shoe quarter comprising outer and lining portions arranged in superposed relation and to perforate the other portion in coöperation with the other punching member.

2. In a machine for setting blind or invisible eyelets, a tubular punching member and a male punching member, the tubular punching member being constructed and arranged to perforate independently one portion of a shoe quarter comprising outer and lining portions arranged in superposed relation and to perforate the other portion 15 in coöperation with the male punching member.

3. In a machine for setting blind or invisible eyelets, a tubular punching member, a male punching member, means for moving the tubular punching member to perforate one portion of a shoe quarter comprising outer and lining portions arranged in superposed relation, and means for moving the male punching member to perforate 25 the other portion in coöperation with the tubular punching member.

4. In a machine for setting blind or invisible eyelets, a tubular punching member, a male punching member, means for moving the tubular punching member to perforate one portion of a shoe quarter comprising outer and lining portions arranged in superposed relation, and means for moving the male punching member into the 30 bore of the tubular punching member to perforate the other portion while the tubular punching member is held at rest.

5. In a machine for setting blind or invisible eyelets, a work support, a tubular punching member movable toward the support to perforate the upper layer of material of a quarter as it rests upon the lower layer of material, and a male punching member movable into the bore of the tubular 45 punching member while the latter is held at rest to perforate the lower layer of the quarter.

6. In a machine for setting blind or invisible eyelets, a male punching member 50 mounted for reciprocation, and a tubular punching member movable first to punch one portion of a quarter at a point at one side of the path of the male member and then transversely into alignment with said 55 member, whereby the other portion of the upper may be punched by both of said members acting in coöperation.

7. In a machine for setting blind or invisible eyelets, a work support for a shoe 60 quarter, a tubular punch movable toward the support to perforate the upper layer of material of the quarter as it rests upon the lower layer of material, and means for subsequently punching a hole in the lower 65 layer.

8. In a machine for setting blind or invisible eyelets, a tubular punching member, and a solid punching member, one of which is constructed and arranged to perforate independently one portion of a shoe quarter, and the other of which is constructed and arranged both to perforate the other portion in coöperation with the punching member first mentioned and to insert an eyelet in the hole thus formed. 75

9. In a machine for setting blind or invisible eyelets, a tubular punching member, and a male punching member, the tubular punching member being constructed and arranged to perforate independently one portion of a shoe quarter, and the male punching member being constructed and arranged both to perforate the other portion in coöperation with the tubular punching member and to guide an eyelet in the 80 hole thus formed. 85

10. In a machine for setting blind or invisible eyelets, a punching member having its end tapered to form a cutting edge, means for forcing said member through one 90 of two layers of sheet material, and means for forcing an eyelet through a hole in the other of said layers and clenching the end of its barrel upon the tapered end of the punching member. 95

11. In a machine for setting blind or invisible eyelets, a male punching member and a tubular punching member having an upsetting surface and being constructed and arranged to perforate independently one 100 portion of a shoe quarter and both to perforate the other portion in coöperation with the male member and to clench an eyelet inserted by the male member.

12. In a machine for setting blind or invisible eyelets, an eyelet carrying tool having a shearing shoulder, a tubular punch having an upsetting surface and being movable to perforate one portion of a shoe quarter, and means for subsequently moving the 110 eyelet carrying tool, first to cause its shearing shoulder to coöperate with the tubular punch for perforating the previously unperforated portion of the quarter, and then to insert an eyelet in the hole thus formed 115 and clench its barrel against the upsetting surface of the tubular punch.

13. In a machine for setting blind or invisible eyelets, a combined tubular punch and upsetting tool having its end shaped 120 for insertion through one layer of the material of a shoe upper, in combination with a combined male punch and eyelet inserting tool.

14. In a machine for setting blind or invisible eyelets, a tubular upsetting tool having a convex tapering upsetting surface immediately adjacent to its end, means for locating said surface between two layers of material, said surface being formed and 125

- arranged for completely upsetting an eyelet barrel between said layers, and means arranged to enter said tool to guide the end of an eyelet barrel against the convex surface.
15. In a machine for setting blind or invisible eyelets, a combined punching and upsetting tool having its end convexly tapered to form a cutting edge and an adjacent upsetting surface.
16. In a machine for setting blind or invisible eyelets, a tubular upsetting tool constructed and arranged for insertion through an aperture in one of a plurality of superposed layers of material and provided with an upsetting surface, immediately adjacent to its end, the internal diameter of said tool being as large as the internal diameter of the barrel of the eyelet to be set, said tool being adapted to upset said eyelet between the superposed layers.
17. In a machine for setting blind or invisible eyelets, means for punching a hole in one of two superposed and contiguous layers of sheet material, and other coöperating means for subsequently punching the other of said layers and inserting an eyelet therein.
18. In a machine for setting blind or invisible eyelets, means for punching a hole in one of two superposed layers of sheet material, means for feeding both of said layers, and means for subsequently punching and setting an eyelet in the other of said layers in register with said hole.
19. In a machine for setting blind or invisible eyelets, punching and feeding means constructed and arranged to punch one portion of a shoe quarter and to feed the entire quarter, and means for punching the other portion of the quarter at the conclusion of the feeding operation.
20. In a machine for setting blind or invisible eyelets, a tubular punch movable to punch independently one portion of a quarter, then to feed the entire quarter, and then to be held stationary, and means for punching the other portion of the quarter in co-operation with the tubular punch while the latter is held stationary.
21. In a machine for setting blind or invisible eyelets, a work support for a shoe quarter comprising an outer and a lining part, means constructed and arranged for movement toward the support through a part of the work to perforate the outer part of the quarter while the latter is yieldingly backed up by the lining part and to clench the barrel of an eyelet between the parts of the work, and a punching tool coöperating with said means to perforate the lining part and form a guide for the insertion of an eyelet through the hole so formed.
22. In a machine for setting blind or invisible eyelets, a tubular punch having inner and outer peripheral surfaces and an end surface which is beveled to constitute an upsetting surface, means for moving said punch to project its beveled end through only one of two superposed layers, a tool constructed and arranged for entering the bore of the tubular punch to guide an eyelet barrel against the beveled end of the punch, and means for advancing an eyelet while so guided.
23. In a machine for setting blind or invisible eyelets, a tool having a tapering surface extending from the end of the tool toward the body of the tool, the vertical extent of said surface being of the magnitude of the thickness of a layer of material so that an eyelet may be upset between superposed contacting layers of material with the tool passing through only one layer, and means for directing the end of an eyelet barrel against said surface.
24. In a machine for setting blind or invisible eyelets, a tool having an exterior peripheral surface, an abruptly tapering end surface extending from the end of the tool toward the body of the tool, an opening in the end of the tool having an interior wall which forms a cutting edge with said exterior tapering surface, said tool being constructed and arranged to punch one of a plurality of superposed layers of material and to upset an eyelet between said layers without entering the barrel of the eyelet, and means for directing the end of an eyelet barrel against said surface.
25. A machine for setting blind or invisible eyelets, having, in combination, a work support for superposed and connected layers of sheet material, a punch movable toward the support sufficiently to perforate some but not all of said layers, the work being fed in this condition to setting position, and means for inserting an eyelet in register with the previously punched hole.

In testimony whereof I have signed my name to this specification.

PERLEY R. GLASS.
